UNITED STATES PATENT OFFICE.

WILLARD E. BARCUS, OF VINELAND, NEW JERSEY.

MEASURING-TANK.

SPECIFICATION forming part of Letters Patent No. 294,181, dated February 26, 1884.

Application filed June 19, 1883. (No model.)

To all whom it may concern:

Be it known that I, WILLARD E. BARCUS, a citizen of the United States, residing at Vineland, in the county of Cumberland and 5 State of New Jersey, have invented certain new and useful Improvements in Measuring-Tanks, of which the following is a specification, reference being had therein to the accompanying drawings.

10 My invention relates to an improvement in measuring-tanks, and while it is adapted especially for measuring molasses, it may be used for measuring liquids of all kinds equally as well; and it consists, first, in the combination 15 of the pipe, which is attached directly to the barrel, the cylinder-head, a perforated plate having on its under side a suitable material for forming a tight joint, and having a flange upon its top, with a stationary plate having 20 two openings through it, and having a groove in its under side, whereby the ingress and egress of the liquid is controlled; second, in the arrangement and combination of parts, which will be more fully described hereinafter.

25 Figure 1 represents a vertical section of my invention complete. Fig. 2 is an inverted view of the same. Figs. 3, 4, 5, 6 are detail views.

A represents the barrel, which has the bung 30 B screwed into it, and which bung-piece is provided with suitable perforations, openings, or slots, by means of which all of the molasses in the barrel will flow through into the measure, and at the same time retain the sugar which 35 has settled to the bottom. This bung-piece is provided with a valve, C, which has connected to it the rod D, by means of which it may be operated. When this valve is raised above its seat, the molasses or other liquid in the 40 barrel can flow freely through, and when the valve is drawn down into the top of the bung all flow is shut off. This bung-piece will be connected to the pipes E E' in any suitable manner, for the purpose of conveying the fluid 45 into the measure. The measure itself is to be attached to the barrel by means of the clamps F, which are formed upon its top. Each clamp consists of a jaw having short projections, and a set-screw for catching against the side of the 50 barrel. By this construction the measure may

be attached directly upon the end of the barrel, and thus supported in position ready to have the fluid drawn from it at any time.

The cylinder G of the measure may be of any desired size, and moving back and forth in this 55 cylinder is the piston H, which has the toothed graduated stem I extending upward from its center, and which stem meshes with the pinion J upon the operating crank-shaft K. By turning the crank-shaft the piston can be 60 raised and lowered at will. The under side of this piston is made slightly convex, so that when it is depressed to the bottom of the cylinder it will not be so liable to stick. The piston will be packed in any suitable manner, 65 so as to move air and fluid tight in the cylinder. In order to enable the operator to know when the lower part of the cylinder has been filled up to the piston, there is an opening made through one side of the piston, and 70 through this opening passes the curved rod L, having the valve N attached to its lower end. This valve N fits in a recess in the lower part of the piston, and as the fluid rises up to the valve it closes this valve, and in closing the 75 valve moves the indicator-rod O downward. The rod which is attached to the valve is pivoted, and as the valve rises upward its operating end, to which the indicator-rod O is attached, is forced downward. As soon as the 80 indicator-rod stops moving the operator knows at once that the cylinder is full up to the piston. The stem which is attached to the piston will be preferably hollowed out upon one side, so as to allow the indicator-rod to pass 85 up through it, and thus always be where it will be readily seen. The stem passes through a spider which is attached to or forms the upper part of the measure, and can be adjusted in its guide by means of suitable set-screws. 90

The bottom or lower head, a, of the measure has an opening, P, through which the fluid, of whatever kind, flows into the measure, and a corresponding opening, Q, through which it flows out. In the top of this bottom 95 piece is made a suitable recess, just above the two openings, and in this recess is placed the valve S, which controls the inlet and outlet flow of the fluid. On the under side of this valve is secured a suitable packing material, 100

c, which forms a tight joint with the openings, and thus prevents any leakage of the liquid in either direction. This valve has a stem or projection, *d*, projecting from its under side 5 through a small opening in the head, and to this stem will be attached the rod or other operating device, by means of which the valve can be turned one-half around. Upon the top of this valve is formed a curved flange, *U*, 10 which fits in a corresponding groove, *V*, in the cap-plate, *W*, which is placed upon the top of the valve. This cap-plate, *W*, has two openings, *X*, through it, one to allow the fluid to flow into the cylinder and the other to flow 15 out. This cap-plate is secured rigidly to the head, and serves to hold the valve down in position. When the valve is turned so that the curved flange enters the curved groove in the cap-plate, the valve is not held tightly 20 against its seat; but when the valve is turned so that the cylinder-flange no longer fits in the groove, the flange acts as a wedge to hold the valve tightly down against its seat. The outlet-opening through the bottom head of the 25 cylinder is shaped or formed so as to enter the mouth of the jug or other similar vessel, and is grooved upon its sides, so as to allow the free escape of air while the jug is being filled. In order to hold the jug in position while being 30 filled, the two arms *Y*, which are pivoted upon the stem *Z*, are used. These arms are curved, so as to catch around the neck of the jug under the flange, and the outer or free ends of the arms are provided with a slide or 35 keeper, *A'*. The edges of the arms may be made notched, so that the keeper will more readily engage with the arms and hold them tightly in position. In order to prevent the arms from being broken from the weight of 40 the jug, a second stem or hanger, *B'*, is provided, and through this stem is passed a rod, *C*, which acts as a support for the ends of the supporting rods or arms. In order to prevent any leakage at any time from the cylinder, 45 there is pivoted upon the same support or hanger as the two holding-arms a cut-off lever, *D'*, which, when turned into position, catches over the opening at the center of the head. As the stem which is attached to the 50 piston is graduated, the operator has but to adjust the piston to the quantity of fluid that is to be drawn from the barrel. By pushing up upon the rod *D*, the valve *C* is removed from its seat, and the fluid flows through the

valve-pipe. By turning the valve so that its opening comes just over the end of the pipe, the fluid flows through into the cylinder until it fills all of the space below the piston. By moving the rotary valve one-half around, so as to make its opening register with the outlet-opening in the cylinder-head, the fluid will either flow out from its own gravity, or may be forced out more rapidly by forcing the piston down to the bottom of the cylinder. In case the vessel to be filled is a jug, as above 65 explained, it will be hung upon the pivotal arms made to support it; but in case it is an ordinary vessel, the arms will not be brought into play. As soon as the cylinder has been exhausted the cut-off arm is moved into position to close the opening, so as to prevent any drip upon the floor. 70

Having thus described my invention, I claim—

1. In combination with a measuring-vessel, 75 the bung-piece *B*, having its inner end shaped as shown, the plug *C*, and the rod *D*, passing through an opening in the side of the bung-piece, whereby the plug can be moved in and out of the mouth of the bung-piece, substantially as shown.

2. In a measuring-vessel, the combination of the rotary valve, having but a single opening through it, and adapted to be turned one-half way around, with the cap-piece provided 85 with two openings, and the head of the cylinder having suitable recesses to receive the two parts, and provided with suitable inlet and outlet openings for the passage of the fluid, substantially as set forth. 90

3. In a measuring-vessel, the combination of the valve, provided with the suitable packing material upon its under side, and having a curved flange upon its top, with the cap-plate, provided with two openings, and having a groove in its under side to receive the curved flange, substantially as specified. 95

4. The combination, with a measuring-vessel, of the pivoted arms and a slide or other device for closing the arms, substantially as shown. 100

In testimony whereof I affix my signature in presence of two witnesses.

WILLARD E. BARCUS.
